METHOD AND MEANS FOR PRODUCING
CONCRETE PIPESAllen L. Braden, Los Angeles, Calif., assignor of
one-half to Hans H. Jorgensen, Los Angeles,
Calif.Application November 14, 1929, Serial No. 407,226
Renewed December 21, 1934

6 Claims. (Cl. 25—30)

My invention relates to a method of and means for producing spun concrete pipes and has particular reference to the manufacture of spun concrete pipes having a connecting bell formed integrally therewith.

In the construction of concrete pipes the usual method followed is to employ a form constructed in accordance with the configuration of the outside of the concrete pipe to be produced, into which form is introduced a charge of concrete mix, and to thereafter rotate the form so that the concrete is pressed outwardly against the form by centrifugal force to produce what is known as a "spun" pipe.

The manufacture of straight sections of pipe by the above noted method is comparatively simple but great difficulty has been encountered in attempting to cast by this method a pipe, with a bell or connecting member formed integrally therewith, since the bell must be of larger diameter than the main body of the pipe, and the opening therethrough must be larger than the opening through the main body of the pipe.

The employment of a form having an enlarged end thereon, with an interior core for the purpose of forming the inner circumference of the bell has been attempted, but pipe constructed by such methods is unsatisfactory because the spinning of the pipe tends to trap the lighter particles of the mix, the water and air, between the core and that portion of the form surrounding the bell, which causes the structure of the bell to be composed largely of slurry. Hence, the bell portion of the pipe is of inferior strength as compared to the main body of the pipe and in some cases the entrapped water prevents the aggregate from entering into the bell portion of the pipe, so that the bell is but partially formed and is of unsound construction.

It is an object of my invention to provide a method of casting by the spinning process a pipe having a bell formed integrally therewith which method will produce a bell construction equal in composition and strength to that of the main body of the pipe.

Another object of my invention is to provide a core or insert which may be placed within the pipe formed during the casting process and which may be readily removed from the form.

Another object of my invention is to provide a core which may be located within the form during the casting of the pipe, which form is so constructed as to permit the escape of water from the bell portion of the form.

Other objects of my invention will be appar-

ent from a study of the following specifications, read in connection with the accompanying drawings, in which—

In the drawings;

Figure 1 is a longitudinal section showing a form with the poured concrete therein.

Fig. 2 is a longitudinal sectional view through a finished pipe including the integral bell coupling at the left hand end in accordance with my improved method.

Figs. 3 and 4 are transverse sections taken on the lines 3—3 and 4—4 respectively of Fig. 1.

Fig 5 is a fragmentary end view showing the green concrete with the annular flanges arranged in the bell portions and subsequently removed to relieve said portions of internal obstructions.

In the drawings, in Fig. 1, the reference character 6 designates the cylindrical portion of the form which is preferably constructed of sections, and at one end is a removable washer 7. At the opposite end is a sectional ring-like portion 8 which defines the external surface of the bell joint. In between is a part 9 which forms the taper between the bell end and the body.

At the left hand end is a closing ring 10 to which one leaf of a hinge 11 is connected. The other leaf of the hinge is elongated and extends across the part 8 and is detachably connected with a keeper 13 on the tapered part 9 of the form.

The principal novel feature of my construction resides in the provision of a mold ring assembly which embodies a plurality of longitudinally spaced units 14, each unit being made up of companion sections 15 and 16. These sections are of annular construction and disposed in meeting contact. By preference the sections 15 and 16 are made up of individual separable segments to facilitate removal and application.

Moreover, the multiple units 14 of the complete assembly, are fastened together by the tie strips or bars 17. I also call attention to the fact that the segments which make up the sections 15 and 16 are of tapered cross section. The result is that when the assembly is in place, it constitutes a mold for shaping a bell joint or coupling of the configuration seen in Fig. 5.

With this arrangement, it will be understood that the tubular body portion of the pipe as indicated at 18 will be of usual configuration and will be joined by a relatively thickened tapered portion 19 with the enlarged part 20 of the bell end. Moreover by the presence of the knock-down ring assembly, I also form the inwardly projecting, longitudinally spaced, annular, tapered, flanges

21. These are however, removed, while the concrete is still green, thus leaving a roughened internal bore in the part 20, as seen in the finished product represented in Fig. 2.
- 5 22. The gist of the invention, it will be understood, is in the provision of the novel ring assembly, wherein the units are made up of companion sections and the sections themselves made of separable segments as seen clearly in Fig. 3. Thus by 10 removing the connecting strips 17, the segments will drop out to facilitate removal, leaving the flanges 21.
- 15 A careful consideration of the description in connection with the drawings, will enable the reader, to obtain a clear understanding of the construction, the method of production, and the means for accomplishing it. Therefore, a more lengthy description is regarded as unnecessary.
- 20 Minor changes in shape, size, materials, and rearrangement of elements, coming within the field of invention claimed may be resorted to in actual practice if desired.
- 25 Having thus described my invention, what I claim as new is:—
- 26 1. In a device for centrifugally producing from a plastic mix a structure having two or more different inner diameters, an outer form for determining the outer configuration of said structure, and an inner form for determining the inner configuration thereof, said inner form having radially extending openings therethrough. 20
- 27 2. In a device for centrifugally producing from a plastic mix a structure having two or more different inner diameters, an outer form for determining the outer configuration of said structure, and an inner form for determining the inner configuration thereof, said inner form having an inner diameter substantially equal to the smallest inner diameter of said structure and 25
- 30 said inner form having radially extending openings therethrough.
- 31 3. In a device for centrifugally producing from a plastic mix a structure having two or more different inner diameters, an outer form for determining the outer configuration of said structure, and an annular inner form having one or more outer diameters to conform with the desired interior configuration of the structure and having a plurality of passages extending from the interior of said inner form to the outer circumference thereof. 5
- 32 4. In a device for centrifugally producing an integral pipe and bell from a concrete mix, an outer form for determining the outer surface of said pipe and said bell, and an annular bell form to determine the inner surface of the bell, said bell form having a plurality of passages for concrete extending radially therethrough. 15
- 33 5. In a device for centrifugally producing an integral pipe and bell from a plastic material, an outer form for determining the outer surface of said pipe and said bell, and an annular bell form to determine the inner surface of the bell, said bell form having an inner diameter substantially 20 equal to the inner diameter of the pipe and having a plurality of passages for concrete extending from the outer surface of said bell form to the inner surface thereof. 25
- 34 6. The method of forming an integral pipe and bell from a concrete mix by the centrifugal process which consists in spinning the concrete mix in a rotating outer form, inserting in said form an inner form of a size to form the inner surface of the bell and having an inner diameter substantially equal to the inner diameter of the pipe and allowing the lighter constituents of the mix to pass through said inner form. 35
